UNITED STATES PATENT OFFICE.

MARTIN HAHN, OF BERLIN, GERMANY, ASSIGNOR TO M. WOELM A. G., OF SPANGENBERG, GERMANY.

AMPUL FOR SUBSTANCES EASILY DECOMPOSABLE IN SOLUTIONS.

Application filed June 15, 1925. Serial No. 37,374, and in Germany June 21, 1924.

By my application Serial No. 628,391, filed March 28, 1923, a storage vessel for easily soluble substances is known in which the solvent and the substance to be dissolved are stored in two separate compartments connected by a capillary tube. The capillary tube is closed by a stopper of paraffin or a mixture of paraffin with wax and resin. This closure has not proved satisfactory in 10 use particularly in hot climates. Its melting point should not be so high that it cannot be removed from the capillary tube without very strong heating. If, however, a mixture of sufficiently low melting point 15 is used then it will be partly softened by the temperatures of the tropics and then attacked by the solution in one compartment, so that after a time it is no longer entirely impenetrable.

20 I have found among easily melted metal alloys, in particular in the known "Wood's" metal, which consists of bismuth, cadmium, tin and lead, and which melts at about 65°, a material without these disadvantages. It 25 does not soften in the tropics, it is in no way affected by water, it remains impenetrable after a long time and when molten is not viscous.

This alloy is not able to resist the action 30 of some acids and of the halogens. To protect it against their action the metal stopper is thinly coated with paraffin, caoutchouc or some other easily melted material which in this case does not form a closure for the capillary tube but only acts as a separating 35 partition between the easily melted metal and the said fluid if present.

In the accompanying drawings Figure 1 40 is a sectional view of both the known form of ampule and the form according to the present invention, the plug *f* in the former case being as above explained of paraffin and wax, and in the latter a fusible metal alloy. Figure 2 is a view of the ampule 45 after insertion of the metal plug and before filling.

When the known double ampule is used, then the lower container *c* (see Figure 1) is dipped in a vessel with warm water far 50 enough to immerse and heat the capillary tube *b* and the easily melted paraffin mixture situated therein. The expanded air in *c* then drives the softened stopper *f* upwards so that the fluid *d* can flow from *a* 55 into *c*.

With this arrangement, however, there are various disadvantages. It is firstly necessary to heat the whole container *c* to a temperature above 50° which may injure certain substances which easily coagulate or 60 decompose on heating.

Secondly it frequently happens that with a single heating the whole quantity of fluid *d* from *a* does not pass on cooling into the compartment *c* because the pressure difference between the two containers is too small. The container *c* must then be dipped again into a warm bath and then cooled again so as to allow the remainder of the fluid *d* to 70 pass into *c*.

According to the present invention these difficulties are avoided in that in filling the ampule a vacuum is made in *c*. To melt the stopper *f* of easily melted material it is simply necessary to heat it with a small 75 flame, whereupon the whole of the fluid in *a* is caused to flow into the evacuated chamber *c* with a speed proportional to the natural air pressure existing in *a*.

The advantages of this new arrangement 80 are obvious. The deleterious heating, once or more than once, of the substance *g* is avoided, and there is no need for a vessel of warm water to cause the materials contained in the two tubes to reach one another. The 85 flame of a match is quite sufficient. Finally it is also advantageous to store the solid substance or solution *g* in an evacuated chamber since many unstable substances for which the double ampule is used are changed 90 by even a small quantity of oxygen.

The double tube is preferably filled, by proceeding in the following manner:

The easily melted metal is first put into a double tube (see Figure 2) open at both ends 95 and provided with a funnel *h* and the substance *g* is then inserted after which the chamber *c* is evacuated and sealed. The fluid *d* is next poured in through the funnel *h* which is then sealed up. Naturally, 100 the fluid can be first passed into the container *a*, this container closed, and then, after inserting *g*, *c* can be evacuated and closed.

If a solution is to be stored in the container *c* instead of a solid substance, for instance suprarenin solution, which is to be used in combination with a novocaine solution, then the easily melted metal is first put 105 into the capillary tube and then the solu- 110

tion d into the tube a , which is sealed and the solution g put into the tube c which is then in its turn evacuated and sealed. In this case the lower opening of c is made so

5 wide that the fluid can be poured in easily.

The tube so filled is particularly useful for the tropics and also for keeping sterile solutions of dry lymph, dry serums and medical substances for intravenous 10 injections against bacterial diseases.

I claim:—

1. In a known sealed glass container comprising two individual ampules and a connecting capillary glass tube closed by an 15 easily fusible material, the closure by an easily melted metal and a pressure difference between the compartments by evacuation of the one, into which the solution is to pass on melting of the metal stopper.

20 2. In a known sealed glass container comprising two individual ampules and a con-

necting capillary glass tube closed by an easily fusible material, the closure by an easily melted metal, the protection of the metal stopper by a chemically inert easily melted substance such as paraffin, caoutchouc or the like on one or both sides of the metal stopper and a pressure difference between the compartments by evacuation of the one, into which the solution is to pass on melting 25 of the metal stopper.

3. A method of filling the double ampule with capillary glass tube, in which the capillary tube of the glass container which has two extensions at first open at both ends is closed by an easily melted metal, after which the two containers filled with the substances are sealed in a known manner, one being previously evacuated.

In testimony whereof I have signed my 40 name to this specification.

MARTIN HAHN.
